(57) **CLAIM**

The ornamental design for an abrasive article with holes, as shown and described.

DESCRIPTION

FIG. 1 is a perspective view of a first side of an abrasive article with holes, as shown;

FIG. 2 is a top view of the first side of the abrasive article;

FIG. 3 is a bottom view of a second side of the abrasive article; and,

FIG. 4 is a front side view of the abrasive article; the left, right,

and back side views being identical thereto.
